UNITED STATES PATENT OFFICE.

CLIFFORD H. RAMSEY, OF PATERSON, NEW JERSEY, ASSIGNOR TO JAMES L. MORRISON MACHINE CO., OF PATERSON, NEW JERSEY, A CORPORATION OF NEW JERSEY.

STOP-MOTION MECHANISM.

1,218,463.

Specification of Letters Patent.

Patented Mar. 6, 1917.

Application filed May 22, 1916. Serial No. 99,203.

To all whom it may concern:

Be it known that I, CLIFFORD H. RAMSEY, a citizen of the United States, residing at Paterson, in the county of Passaic and State 5 of New Jersey, have invented certain new and useful Improvements in Stop-Motion Mechanisms; of which the following is a specification.

In machines known as "dye-becks", in 10 which fabrics and the like are drawn lengthwise through dyeing or other liquids in a vat by means of a rotating drum, there is employed what is termed a "rake" over which the fabrics extend on their way from 15 the liquid in the vat to the drum, the several fabrics, each of which has its ends fastened together to make it endless and is rolled more or less into the form of a rope for the purpose of treatment in the machine, being 20 kept separate by the arms or tines of the rake. Snarls, wads or clumps of the fabric occasionally catch on the rake or some other part around which they extend and stop the 25 progress of the fabric, in consequence of which the same becomes chafed by the drum unless its rotation is immediately arrested by the attendant.

The object of this invention is to provide 30 a reliable and simple means for automatically stopping the rotation of the drum when the fabric from any such cause as that indicated above exerts unusual pressure on the rake; and in accomplishment of this object I make the rake movable under actuation 35 of the fabric and adapted to actuate means which controls the rotation of the drum. I construct the mechanism so that the resistance to movement of the rake may be regulated to suit the ability of the fabric 40 being treated to stand strains and the like, so that when regulated it will not operate until the condition arises upon which its operation is predicated, and so that when it does operate it shall do so in a way to certainly and instantly lead to the stopping of 45 rotation of the drum.

In the accompanying drawings,

Figure 1 is a side elevation of a dye-beck 50 embracing my improvements; Figs. 2 and 3 are vertical sectional views on the lines $x-x$ and $y-y$, respectively, of Fig. 1, looking toward the right;

Fig. 4 is a fragmentary plan view, showing 55 the principal parts of the stop motion mechanism;

Fig. 5 is a front elevation of what is shown in Fig. 4, excepting that a part of the rake is shown in section;

Figs. 6 and 7 are a plan and a side elevation of the rake; and,

Figs. 8 and 9 are a side elevation and a sectional view on the line $z-z$ in Fig. 8, respectively, of a certain cam.

a is a vat and b uprights bolted to the sides thereof and affording above the vat 65 bearings for the shaft c of the reel or drum d . The shaft has loose thereon, between one of the uprights b and a bracket e supporting one end of the shaft, a pulley f and there is a clutch one member g of which is attached 70 to the pulley and the other member h of which is splined on the shaft. Around the pulley may extend a driving belt (not shown).

The pieces of fabric to be treated, each 75 having its ends secured together to give it endless form and being rolled into the shape of a rope, extend around the drum, under a vertical partition i in the vat and around the rake. The drum rotates in the direction of 80 the arrow in Fig. 1.

The rake, including a series of parallel arms or tines for keeping separated the fabrics and a roller around which the fabrics extend, in the usual construction is stationary. According to the present invention the rake is movable, in the instance herein particularly shown being adapted to tilt and constructed as follows: j denotes a cross-piece from which project the parallel arms 85 or tines k to form the rake proper and which is equipped at each end with a bracket l having set into it and suitably secured therein by a set screw m a rod n , each bracket and rod forming in effect a bell-crank lever. 90 The brackets l afford journals for a roller o arranged above and in a plane parallel with the arms or tines k of the rake proper, this being the roller around which the fabrics pass, separated by the arms or tines of the 95 rake proper; on each of the rods n is a weight p adjustable longitudinally of the rod. The rake, thus constructed, is fulcrumed in brackets q upstanding from the sides of the vat, the fulcra being pins r in 100 brackets q entering holes s in the brackets l of the rake.

To one side of the vat is secured an up-standing bracket t in the upper end of which, on a horizontal pin u parallel with the side 110

of the vat, is fulcrumed an arm v having a curved cam slot w in a curved projection x of the arm, said arm carrying, adjustable lengthwise thereof, a weight y shaped preferably as a handle. The end of cam slot w which is remote from the fulcrum of the arm approximates (though actually shown as slightly curved) the chord of a circle having said fulcrum for its center (see Fig. 8). On the side of the bracket t which adjoins the vat said bracket has a ledge z on which the adjoining bracket l of the rake rests in the normal position of the rake. This ledge supports the rake in such a position, with its center of gravity somewhat past the perpendicular through its axis of movement, that the axis of roller o is slightly above the horizontal plane of the fulcrum r of the rake, for a purpose to be explained. In bracket t and a bracket 2 is journaled a horizontal rock shaft 3 carrying at its ends the arms 4 and 5 . Arm 4 has a stud 6 engaged in the aforesaid cam slot. Arm 5 is connected by a link 7 to one end of a fork-lever 8 fulcrumed in bracket e and having its fork engaging a peripheral groove in the clutch member h . Arm v is limited by stud 6 to move from an upright position with its center of gravity somewhat past the perpendicular through its axis of movement (dotted lines, Fig 5) to a substantially horizontal position (full lines, Fig. 5). It has an inclined face which overlies bracket l of the rake when said arm is in the upright position and the bracket abuts ledge z . The train of parts v , 4 — 3 — 5 , 7 , 8 and h , once the arm v is moved from the dotted line position past the perpendicular through its axis of movement, is normally moved (by gravity acting on said arm) to disestablish the clutch, and when arm v is in the dotted line position it serves to lock said train against such movement. In the normal position of the parts, the rake rests against stop z , its arms or tines touching a perforated diaphragm i' , Fig. 3 (which separates from the fabric-receiving or larger part of the vat the part in which the dye materials are introduced) so as to prevent the fabrics working under the tines; the arm v has been turned up past its dead center (i. e., so that its center of gravity is past the perpendicular through its axis of movement) to the dotted line or locked position, which movement, through cam x — w , has rocked shaft 3 and so shifted the clutch member h into engagement with clutch g to cause the drum to be driven and thus advance the fabrics through the liquid in the vat. The weights p are adjusted by the attendant so that, without imposing undue strain on the fabrics being treated while they continue in the normal way to be drawn over the roller of the rake, the rake will tilt when such an obstruction (as a snarl or

clump of one of the fabrics) engages the rake as would stop the progress of that fabric if the rake were fixed, or when, if any fabric becomes obstructed at some other point, as at the partition i , the incidental increased tension on the fabrics causes the rake (whose roller is then above the horizontal plane of the axis of movement of the rake) to be thrown over past the perpendicular through its axis of movement. The limit of movement of the rake is determined by contact of its weights p with the sides of the vat. On the rake being thrown over, its arm l impinges against the face 9 on arm v , of what I term the actuating member v , y , 80 x , which is in turn thrown over past its center of gravity, coming to rest in the approximately horizontal position with the inner end of its cam-slot against stud 6 and incidentally rocking the rocking or actuated member 4 , 3 , 5 , and so, through link 7 and lever 8 , disengaging clutch member h from clutch member g , thus cutting off the power from the drum.

Having cleared the obstruction, the attendant returns the rake to working position and resets the arm v , thereby reestablishing the clutch to start the drum again rotating.

When the rake is thrown over to rest against the sides of the vat (dotted lines, Fig. 1) it stands in inoperative position, so that the attendant is warned against starting up the machine, by returning the arm v to normal position, until the obstruction has been cleared.

The part of cam-slot w which, as aforesaid, is slightly curved, approximating the chord of a circle allows arm v to pass its center of gravity from normal position with a certain lost motion before affecting the rocking structure 3 , 4 , 5 and the parts 7 , 8 and h moved thereby, and then to move them quickly when its fall occurs; the strain on the fabric responsible for the movement of the rake is by this reduced to such as is involved only in moving the arm v past its center of gravity and not the whole train of parts v , 3 — 4 — 5 , 7 , 8 and h .

Having thus fully described my invention, what I claim as new and desire to secure by Letters Patent is:

1. In a machine for treating fabrics and similar materials with liquids, the combination of a supporting structure including a vat, means to advance the material through the vat, movable means for controlling the first means, and a material-actuated rake over which the material extends movable into impact with and thereupon adapted to actuate the second means.

2. In a machine for treating fabrics and similar materials with liquids, the combination of a supporting structure including a vat, means to advance the material through the vat, movable means for controlling the

- first means, and a pivoted material-actuated rake over which the material extends movable into impact with and thereupon adapted to actuate the second means.
- 5 3. In a machine for treating fabrics and similar materials with liquids, the combination of a supporting structure including a vat, means to advance the material through the vat, movable means for controlling the 10 first means, a pivoted material-actuated rake over which the material extends movable against and thereupon adapted to move the second means and regulating means for the rake.
- 15 4. In a machine for treating fabrics and similar materials with liquids, the combination of a supporting structure including a vat, means to advance material through the vat, a tiltable rake over which the material 20 extends normally resting with its center of gravity at one side of the perpendicular through its axis of tilting movement and adapted to be tilted by the material past said perpendicular, and means, arranged to be 25 engaged by the rake after it tilts past the perpendicular, for controlling the first means.
5. In a machine for treating fabrics and similar materials with liquids, the combination 30 of a supporting structure including a vat, means to advance material through the vat, means for controlling the first means having a locking member, and a rake over which the material extends movable against 35 and adapted to release said member.
6. In a machine for treating fabrics and similar materials with liquids, the combination 40 of a supporting structure including a vat, means to advance material through the vat, means for controlling the first means having a fulcrumed locking member movable over its fulcrum past the perpendicular through said fulcrum to locking position, and a rake over which the material extends 45 movable against and adapted to move said member from its locking position past said perpendicular.
7. In a machine for treating fabrics and similar materials with liquids, the combination 50 of a supporting structure including a vat, means to advance material through the vat, means for controlling the first means having a locking member, and material-actuated means to release said member.
- 55 8. In a machine for treating fabrics and similar materials with liquids, the combination 60 of a supporting structure including a vat, means to advance material through the vat, means for controlling the first means having a fulcrumed locking member movable over its fulcrum past the perpendicular through said fulcrum to locking position,
- and material-actuated means to move said member from its locking position past said perpendicular.
9. In a machine for treating fabrics and similar materials with liquids, the combination of means to advance material, and controlling means therefor including a material-actuated member, and a power-transmitting 70 train including a tilting member movable over and past the perpendicular through its axis of tilting movement to rest position, the first-named member being movable against and adapted to shift the other member 75 from rest position past said perpendicular.
10. In a machine for treating fabrics and similar materials with liquids, the combination of means to advance material, and controlling means therefor including two tilting members, one movable past the perpendicular through its axis of tilting movement to rest position and the other being material-actuated and movable against and adapted 80 to shift the first-named member past said perpendicular.
11. In a machine for treating fabrics and similar materials with liquids, the combination, with means to advance material, of 90 means to control the advance of the material including a supporting structure, a normally moved train of parts including an actuated member and a locking actuating member connected together, the latter member being 95 pivoted and having limited movement in one direction past its dead center, and material-actuated means to move said latter member in the other direction.
12. In a machine for treating fabrics and similar materials with liquids, the combination, with means to advance material, of 100 means to control the advance of the material including a supporting structure, a rocking member fulcrumed therein, a fulcrumed 105 cam-including member having its cam portion engaged with said rocking member and movable over, and past a perpendicular through, its fulcrum to rest position, and material-actuated means to move the second- 110 named member from rest position past said perpendicular.
13. In a machine for treating fabrics and similar materials with liquids, the combination of a supporting structure including a 115 vat, means to advance material through the vat, a fulcrumed rake movable over, and past a perpendicular through, its fulcrum to rest position, and movable reversely under pressure of the fabric past said perpendicular, and means, controlled by the rake, for 120 controlling the first means.

In testimony whereof I affix my signature.
CLIFFORD H. RAMSEY.
